UNITED STATES PATENT OFFICE.

HARRY A. RIGGS, OF ST. LOUIS, MISSOURI.

HANDLE.

Application filed July 21, 1919. Serial No. 312,125.

To all whom it may concern:

Be it known that I, HARRY A. RIGGS, a citizen of the United States, residing in the city of St. Louis and State of Missouri, have 5 invented certain new and novel Improvements in Handles, of which the following is a specification.

My invention relates to handles, and more particularly to a handle, or carrier for ready 10 and quick attachment to containers, such as fruit-jars, milk-bottles, and the like having flanged or flaring tops.

The object of my invention is to provide 15 a handle, or carrier which will be cheap to manufacture and which can be easily and quickly applied to the neck of a container such as a bottle, jar or the like, to permit the same to be carried like a pail, or bucket, and which can be as quickly detached from 20 the container when desired.

With the above and other objects in view, the invention consists in the novel features of construction, arrangement and combination of parts, hereinafter fully described and 25 finally pointed out in the claim hereto appended.

Referring to the accompanying drawings forming a part of this specification wherein like characters of reference denote similar 30 parts throughout the several views:

Fig. 1, is a top plan view of a handle constructed in accordance with my invention, a part thereof being broken away.

Fig. 2, is an elevation of my improved 35 handle showing same applied to the neck of a Mason-jar.

Fig. 3, is a side elevation of the handle.

Fig. 4, is an elevation of the handle showing same applied to the neck of a milk-bot- 40 tle.

Referring to the drawings the reference character 1 designates an ordinary Mason-jar having the usual contracted neck 2 and flange 3 below the screw-threaded portion 45 thereof which receives the screw-threaded cover cap 4. The reference character 5 indicates a milk-bottle having the usual upwardly and outwardly flaring neck 6 terminating in the beaded top 7.

50 In carrying out the aim of my present invention, I employ, preferably, a holder member made from a single-strand of suitable spring-wire. The holder-member is formed by bending the wire to form a 55 semi-circular member 8. The remaining

end pieces of the wire 8 are then bent outwardly to form laterally extending arms 9, each of which arms terminate in an upwardly extending oppositely disposed side looped ear 10. Each looped ear 10 terminates in 60 an inwardly extending arm 11 running parallel with the arms 9. The arms 11 each terminate in the short curved members 12, which are of the same radius as the semi-circular member 8. The short curved members 65 terminate in outwardly diverging guide arms 13, which in turn, preferably, although not necessarily, terminate in the looped ends 14.

It will be here observed, that an open 70 space or mouth 15 is provided, or formed between the short curved holder members 12 where they join the outwardly diverging guide arms 13, so as to permit the holder members to be quickly and easily slipped 75 or snapped into position when applying the same to the neck of fruit-jars, milk-bottles, or similar containers.

A suitable stirrup-shaped wire bail 16 is connected at its looped ends 17 to the opposed side looped ears 10 and is preferably, although not necessarily, provided with a suitable wooden grip handle 18.

When applying the holder-member to a container, it is necessary, owing to the fact 85 that the mouth 15 of the holder is less in width than the diameter of the semi-circular holder member 8 at a point in line with the ears 10, to expand the short curved holder members 12 outwardly when forcing the device onto the neck of a container, as is manifest. When the holder has been positioned, it is evident that, owing to the fact that the holder is resilient, it will frictionally engage the neck of the container and permit the container to be carried like a bucket. The holder cannot slip off of the neck as it encircles more than half of the neck and the container cannot slip through the holder member owing to the fact that the holder 100 member is always applied at a point where that portion of the container above the holder is larger in diameter than the inside of the holder, or provided with a flange or bead for engagement with the upper surface of the holder, as is manifest.

It is apparent that the holder can be readily applied to any container having a neck of a diameter equal to the inside diameter of the holder, or larger, thus per- 110

mitting the use of a single holder to accommodate itself for carrying containers having various sized necks.

The object of having the bail receiving 5 ears 10 positioned out further than the outside diameter of the curved holder is to permit application of the holder to jars, or containers having a flange, or bead arranged above the holder such as flange 3, shown in 10 Fig. 2.

It will be observed that the holder can be applied to and used in connection with any container, jar, or bottle which is so formed as to prevent the same from slipping 15 through the holder when applied thereto.

From the foregoing, it will be evident that the device can be cheaply made, easily and quickly applied to a container for carrying the same, and the many advantages of a 20 device as herein described will readily suggest themselves to those skilled in the art to which it appertains.

I do not desire to be understood as limiting myself to the details of construction and 25 arrangement as herein described and illustrated, as it is manifest that variations and

modifications may be made in the features of construction and arrangement in the adaption of the device to various conditions of use without departing from the 30 spirit and scope of my invention and the terms of the following claim, hence wish it to be understood that I reserve the right to make any such changes or modifications as may fairly fall within the scope of the 35 appended claim when fairly construed.

What I claim is:

A device of the class described, comprising a curved resilient wire holder having opposed laterally extending arms formed in 40 integral with the holder terminating in upwardly extending loops beyond the outer diameter of said holder, a bail connected to said loops and the ends of said holder terminating in diverging guide arms for 45 force contact with the wall of a container to gradually expand the holder when applying the holder to a container.

In testimony whereof, I have hereunto signed my name to the specification.

HARRY A. RIGGS.
